(57) **CLAIM**

I claim the ornamental design for flush controller for sanitary fixtures, as shown and described.

DESCRIPTION

FIG. 1 is a top and front and right side isometric view of a flush controller for sanitary fixtures showing my new design; FIG. 2 is a front view of the flush controller for sanitary fixtures;

FIG. 3 is a rear view of the flush controller for sanitary fixtures;

FIG. 4 is a top view of the flush controller for sanitary fixtures;

FIG. 5 is a bottom view of the flush controller for sanitary fixtures;

FIG. 6 is a right side view of the flush controller for sanitary fixtures; and,

FIG. 7 is a left side view of the flush controller for sanitary fixtures.

The control stop fitting and pipe shown in broken lines in FIG. 1 are included to show the environment for the flush controller for sanitary fixtures and are not part of the design.
